ARC TUBE MOUNT

Hugh D. Fraser, West Caldwell, and Melvin C. Unglert, Wyckoff, N.J., assignors to Westinghouse Electric Corporation, East Pittsburgh, Pa., a corporation of Pennsylvania

Filed Oct. 30, 1957, Ser. No. 693,395

7 Claims. (Cl. 313—25)

This invention relates to high-pressure, electric-discharge devices and, more particularly, to an improved arc tube mount construction for a high-pressure, electric-discharge device.

High-pressure, mercury-vapor lamps are well known and are generally described in U.S. Patent No. 2,748,303 to Thorington. Such lamps generally comprise an inner arc tube which encloses the mercury discharge during lamp operation and an outer envelope surrounds the inner arc tube. The outer envelope may be left clear or may be coated with a phosphor material.

One of the most troublesome problems in the manufacture of such lamps is the construction of the arc tube mount and a typical construction is shown in Fig. 1 of the aforesaid patent to Thorington. Such a typical mount construction normally comprises a wire frame with metal bridges and the frame and bridges are normally welded together. In addition metal springs, which are also welded to the frame, position the arc tube mount within the outer bulb. The multiplicity of welds and bending of wires makes such a construction quite expensive and troublesome. For example, in the case of failure of one or more of the welds, the arc tube is apt to slip from its positioning within the outer envelope and cause a lamp failure. Also the bending of wires and the individual welding procedures required to form the mount structure are exacting and expensive.

It is the general object of this invention to avoid and overcome the foregoing and other difficulties of and objections to prior-art practices by the provision of a high-pressure, electric-discharge device having a mount which is extremely durable and which will not allow the arc tube to move within the outer envelope, even with failure of one or more of the mount-forming portions.

It is another object to provide a high-pressure, electric-discharge device having an arc tube mount which can be readily and cheaply fabricated on a mass-production basis with a minimum of individual fabrication operations.

It is a further object to provide an assembly incorporating an arc tube and the mount therefor for fabricating a high-pressure, electric-discharge device, wherein the assembly is extremely rugged, inexpensive to fabricate and can be readily handled during lamp fabrication.

The aforesaid objects of the invention, and other objects which will become apparent as the description proceeds, are achieved by providing a high-pressure, electric-discharge device having an arc tube mount which comprises two adjacent metal frames, each of which have two end-connected longitudinal members positioned on opposite sides of the arc tube and spaced apart therefrom. The arc tube is provided with seals extending from either end thereof, as is customary, and transverse frame members, which connect across each of the longitudinal members of the frame, supportingly engage the extending seal portions of the arc tube. Desirably, the transverse members which support the arc tube are bent in complementary fashion to conform to the seal portions

2

of the arc tube. The metal frames are secured to one another, preferably by spot welding in a plurality of locations, to maintain the frames in their adjacent relationship, even with failure of one or more of the individual welds, for example. The arc tube and mount form an assembly which can be readily handled without failure and which provides a very strong construction when incorporated into a lamp.

For a better understanding of the invention, reference should be had to the accompanying drawing wherein:

Fig. 1 is an elevational view, partly in section, of a high-pressure, mercury-vapor lamp incorporating the improved arc tube mount construction;

Fig. 2 is a side elevation, partly in section, of the lamp as shown in Fig. 1;

Fig. 3 is a fragmentary sectional view taken on the line III—III in Fig. 1 in the direction of the arrows;

Fig. 4 is a sectional view taken on the line IV—IV in Fig. 2 in the direction of the arrows;

Fig. 5 is a sectional view taken on the line V—V in Fig. 1 in the direction of the arrows;

Fig. 6 corresponds to Fig. 4, but illustrates an alternative embodiment for the arc tube mount construction;

Fig. 7 corresponds to Fig. 5, but illustrates an alternative arc tube mount construction;

Fig. 8 corresponds to Fig. 5, but illustrates a further alternative arc tube mount construction;

Fig. 9 is a small-scale elevational view of a still-further alternative arc tube mount construction.

Although the principles of the invention are broadly applicable to any type of electric-discharge device which involves a dual-envelope construction, the invention is usually employed in conjunction with high-pressure, mercury-vapor lamps and hence it has been so illustrated and will be so described.

With specific reference to the form of the invention illustrated in the drawing, the numeral 10 in Figs. 1 and 2 indicates generally a high-pressure, mercury-vapor lamp which comprises a light-transmitting outer envelope 12,

40 which may be fabricated of a vitreous material such as hard or soft glass. The outer envelope 12 has a dome portion 14 which may take the form of a small protrusion which assists in providing support for the arc tube mount. The outer envelope 12 also has a neck portion

45 16 to which the lamp base 18 is secured and the outer envelope 12 is hermetically sealed at its neck 16 by means of a reentrant stem press 20, as is customary in the art. The outer envelope preferably encloses a nitrogen-gas fill at a pressure of about 500 millimeters, for example,

50 although other inert-gas fills or vacuum could be used if desired. Sealed through the reentrant stem press 20 and electrically connected to the lamp base 18 are two lamp lead conductors 22 and 24, as is customary, and these are electrically connected to the arc tube 26, as ex-

55 plained in detail hereinafter. The outer envelope may be left clear, if desired, or it may be coated with a phosphor material such as described in the aforementioned Thorington patent, for example.

The arc tube 26 is of generally-standard construction 60 and comprises a light-transmitting envelope 28, normally fabricated of quartz, or in some cases Vycor, having seals 30 extending from either end thereof. Arc tube lead conductors 32 are hermetically sealed through the arc tube seals 30 with a conventional ribbon-seal technique and

65 are electrically connected to electrodes 34 operatively disposed within the arc tube at either end thereof. For purposes of electron-emissivity a thorium sliver, for example, is desirably included as a part of the electrodes 34, which may be fabricated of tungsten, for example, and such electrode constructions are well known. A starting electrode 36 is desirably positioned within the arc tube proximate one operating electrode and is connected to the

70

same electrical potential as the opposite arc tube electrode through a resistor 38, such as a 15K resistor, as is usual in such lamp designs. The arc tube contains a selected charge of mercury and an inert ionizable gas such as 20-25 mm. of argon, for example. The mercury charge may be controlled such as by a method as taught in U.S. Patent No. 2,755,159 to Bernier et al., for example.

The arc tube mount 40 which supports the arc tube in position within the outer envelope generally comprises two adjacent metal frames 42 and 44. These metal frames are desirably punched into a predetermined configuration from sheet stock, such as 10 mil nickel-plated-iron sheet stock, for example. Each adjacent metal frame generally comprises two longitudinal members 46 which are positioned on opposite sides of the arc tube 26 and are spaced apart therefrom. The longitudinal members 46 of the metal frames are connected at their ends for purposes of rigidity and in the embodiment as shown, the upper ends of the metal frames each have a configuration similar to that of the dome 14 of the outer envelope 12, in order to inhibit any lateral motion of the mount 40 within the outer envelope. Each of the bottom ends of the frame longitudinal members 46 are connected by transverse frame members in the embodiment as shown, although the frame constructions could be made symmetrical, if desired, so that the bottom frame portions would have configurations similar to the frame top portions which are illustrated in Figs. 1 and 2. Each frame has an upper transverse member 48 and a lower transverse member 50 which connect across each of the longitudinal members 46 and supportingly engage the extending seal portions 30 of the arc tube 26. The metal frames preferably are spot welded to one another in a plurality of locations 52 to maintain them in adjacent relationship and to secure the arc tube firmly.

In Fig. 3 is shown a plan view of the upper frame transverse members 48 and upper seal portion of the arc tube 26 and as illustrated, the frame transverse members 48 desirably are bent in complementary fashion so as to conform to the configuration of the upper seal portion of the arc tube 26 to firmly secure same. Such a construction is illustrated in section in Fig. 5 and the lower transverse members 50 desirably have a similar configuration.

The punched metal frames 42 and 44 may have a flat cross-sectional configuration, as shown in Fig. 4, but it may be desirable to punch the frames so that they have a non-planar (or as otherwise expressed, multi-planar) cross-sectional configuration. This serves to increase the frame strength in a lateral direction. Such a non-planar cross-sectional configuration may take many different forms, but it has been found convenient to punch a ribbed configuration into the frames and such an alternative embodiment is shown in Fig. 6.

In the preferred form of the invention the frame transverse members 48 and 50 are bent in complementary fashion so as to conform to the configuration of the seal portions 30 of the arc tube 26. The frame transverse members, however, need not conform to the seal portions of the arc tube, but may be formed so that the frame transverse members are bent about the arc tubes during fabrication of the mount and arc tube assembly. Such an embodiment is illustrated in Fig. 7 wherein the spring action of the metal transverse members 48a exert a force on the arc-tube seals to maintain same in position. In the preferred form of the invention the arc-tube seals 30 have been of the pinch-type so that they have a generally flattened cross-sectional configuration. The seals may also have a generally-circular cross-sectional configuration, for example, and such an alternative seal embodiment 30a is also shown in Fig. 7.

In fabricating the arc tube and mount assembly, the metal frames are first punched out of the sheet stock as indicated hereinbefore. Two of the frames are then placed in adjacent relationship with the arc tube in the desired position and the frames and arc tube desirably

are clamped into a jig. The adjacent metal frames are then preferably spot welded in a plurality of locations in order to maintain the arc-tube-securing frames in their adjacent and arc-tube-securing relationship. Desirably the metal frames are welded to one another at least at the corners which are formed by the transverse members and the longitudinal members, but since the multiple spot welds may be accomplished in one operation with a standard welding jig, many more weld locations may be provided without any appreciable increase in cost and labor. Simultaneously the reentrant stem press and lead conductors may be electrically connected to the arc tube mount 40 and one of the lead conductors 22 may be welded directly to the mount 40 in order to provide support and facilitate electrical connection to the upper electrode of the arc tube. To finish the lamp fabrication, the arc tube lead conductors are welded to the lamp lead conductors, or frame as indicated, the starting resistor welded in place and the arc tube and mount assembly inserted into the outer envelope until the upper ends of the adjacent frames 42 and 44 contact the dome portion 14 of the outer envelope 12. Thereafter the outer envelope 14 is hermetically sealed by the usual techniques. The lamp base is then secured to the neck of the lamp by conventional practices and the lamp lead conductors 22 and 24 electrically connected thereto.

The fabrication of the foregoing arc tube and mount assembly is quite simple and only involves a stamping and one main welding operation. The arc tube mount is extremely rugged and able to withstand the shocks of fabrication and service better than the mount constructions of the prior art. In addition, even if one or more of the spot welds break, as long as sufficient welds remain intact to maintain the frames comprising the mount in their adjacent relationship, the arc tube will be maintained in position within the outer envelope and the lamp will function properly.

It will be recognized that the objects of the invention have been achieved by providing a high-pressure, electric-discharge device having an arc tube mount which is extremely durable and which will not allow the arc tube to move within the outer envelope, even though one or more of the mount-forming welds fail. In addition, the mount for the arc tube can be readily and cheaply fabricated on a mass-production basis with a minimum of individual fabrication operations. There has also been provided an arc tube and mount assembly for incorporation into a high-pressure electric-discharge device, which assembly is extremely rugged and can be readily handled during lamp fabrication.

As an alternative embodiment, the spot welds which maintain the frames in their adjacent relationship may be replaced by rivets 54 as shown in Fig. 8. Also, tabs may be provided on the frames and these may be crimped over the adjacent frame to secure them together. From the standpoint of cost and performance, however, a spot welding technique is preferred in forming the instant mount.

In the preferred embodiment of the arc tube mount as described hereinbefore, the longitudinal members 46 of each of the punched metal frames 42 and 44 are connected at their ends for purposes of rigidity and additional transverse members connected across the longitudinal members of the frames and are conformed to support the arc tube in position. As an alternative construction, the end connections for the frame longitudinal members may be effected by the transverse members which also support the arc tube. Such an alternative embodiment is illustrated in Fig. 9 wherein the frame transverse members 48 and 50 which support the arc tube also serve the dual function of providing end connections for each of the frame longitudinal members 46 to provide rigidity. Additional support members 56 and 58 may then be provided on the frame to cooperate with the dome portion 14 of the outer envelope 12 and with

the lead conductor 22 to support the arc tube mount in position within the outer envelope.

While in accordance with the patent statutes one best-known embodiment of the invention has been illustrated and described in detail, it is to be particularly understood that the invention is not limited thereto or thereby.

We claim:

1. A high-pressure electric-discharge device comprising: a light-transmitting outer envelope; an inner light-transmitting arc tube having a seal extending from either end thereof and a mount supported within said outer envelope and supporting said arc tube in position within said outer envelope; said mount comprising, two adjacent metal frames each having longitudinal members positioned on opposite sides of said arc tube and spaced apart therefrom, transverse members connecting across each of the longitudinal members of said frames and supportingly engaging the extending seal portions of said arc tube, and said metal frames secured to one another in a plurality of locations to maintain said frames in adjacent relationship.

2. A high-pressure electric-discharge device comprising: a light-transmitting outer envelope; an inner light-transmitting arc tube having a seal extending from either end thereof; and a mount supported within said outer envelope and supporting said arc tube in position within said outer envelope; said mount comprising, two adjacent generally-flat metal frames each having end-connected longitudinal members positioned on opposite sides of said arc tube and spaced apart therefrom, transverse members connecting across each of the longitudinal members of said frames and supportingly engaging the extending seal portions of said arc tube, and said metal frames welded to one another in a plurality of locations to maintain said frames in adjacent relationship.

3. A high-pressure electric-discharge device comprising: a light-transmitting outer envelope; an inner light-transmitting arc tube having a seal extending from either end thereof; and a mount supported within said outer envelope and supporting said arc tube in position within said outer envelope; said mount comprising, two adjacent generally-flat metal frames each having end-connected longitudinal members positioned on opposite sides of said arc tube and spaced apart therefrom, transverse members connecting across each of the longitudinal members of said frames and supportingly engaging the extending seal portions of said arc tube, said transverse members bent in complementary fashion conforming to the seal portions of said arc tube, and said metal frames welded to one another in a plurality of locations to maintain said frames in adjacent relationship.

4. A high-pressure electric-discharge device comprising: a light-transmitting outer envelope; an inner light-transmitting arc tube having a seal extending from either end thereof; and a mount supported within said outer envelope and supporting said arc tube in position within said outer envelope; said mount comprising, two adjacent metal frames having a non-planar cross-section to increase the frame strength in a lateral direction, each of said frames having two end-connected longitudinal members positioned on opposite sides of said arc tube and spaced apart therefrom, transverse members connecting across each of the longitudinal members of said frame and supportingly engaging the extending seal portions of said arc tube, said transverse members bent in complementary fashion conforming to the seal portions of said arc tube, and said metal frames welded to one another in a plurality of locations to maintain said frames in adjacent relationship.

5. A high-pressure electric-discharge device comprising: a light-transmitting outer envelope; an inner light-transmitting arc tube having a seal extending from either end thereof; and a mount supported within said outer

envelope and supporting said arc tube in position within said outer envelope; said mount comprising, two adjacent metal frames having a ribbed cross-section to increase the frame strength in a lateral direction, each of said frames having two end-connected longitudinal members positioned on opposite sides of said arc tube and spaced apart therefrom, transverse members connecting across each of the longitudinal members of said frame and supportingly engaging the extending seal portions of said arc tube, said transverse members bent in complementary fashion conforming to the seal portions of said arc tube, and said metal frames welded to one another in a plurality of locations to maintain said frames in adjacent relationship.

10 6. An assembly for insertion into an open-ended light-transmitting envelope for an electric-discharge device, said assembly comprising an arc tube having a seal extending from either end thereof, an arc-tube mount for supporting said arc tube in position within said outer envelope, said mount comprising two end-connected adjacent metal frames each having two longitudinal members positioned on opposite sides of said arc tube and spaced apart therefrom, transverse members connecting across each of the longitudinal members of said frames and supportingly engaging the extending seal portions of said arc tube, said transverse members bent in complementary fashion conforming to the seal portions of said arc tube, and said metal frames welded to one another in a plurality of locations to maintain said frames in adjacent relationship.

20 7. A high-pressure electric-discharge device comprising: a light-transmitting outer envelope having a dome and a neck; a base secured to the neck of said outer envelope; an inner light-transmitting arc tube longitudinally disposed within said outer envelope and having a seal enclosing an arc-tube lead conductor extending from either end thereof; lamp lead conductors electrically connecting to said base, sealed through said outer envelope and operatively connecting to said inner arc tube; and a mount supporting said arc tube in position within said outer envelope and facilitating electrical connection for said arc tube; said mount comprising, two adjacent generally flat metal frames each having two end-connected longitudinal members positioned on opposite sides of said arc tube and spaced apart therefrom, transverse members connecting across each of the longitudinal members of said frames and supportingly engaging the extending seals of said arc tube, said transverse members bent in complementary fashion conforming to the seal portions of said arc tube, said metal frames welded to one another in a plurality of locations to maintain said frames in adjacent relationship, the portions of said adjacent frames adjacent the dome of said outer envelope cooperating therewith to provide frame support, one of said lamp lead conductors connecting to the portion of said frame proximate the neck of said lamp to provide frame support within said outer envelope, and the lead conductor of said arc tube which is closest the dome portion of said lamp electrically connecting to said frame.
